UNITED STATES PATENT OFFICE.

HOWARD H. SCHOTT, OF ROCHESTER, NEW YORK, ASSIGNOR TO ROBESON-ROCHESTER CORPORATION, OF ROCHESTER, NEW YORK, A CORPORATION OF NEW YORK.

DESIGN FOR AN URN.

Application filed April 13, 1927. Serial No. 21,574. Term of patent 7 years.

To all whom it may concern:

Be it known that I, HOWARD H. SCHOTT, a citizen of the United States, residing at Rochester, in the county of Monroe and State of New York, have invented a new, original, and ornamental Design for Urns, of which the following is a specification, reference being had to the accompanying drawing, forming part thereof.

I claim:
The ornamental design for an urn as shown.

HOWARD H. SCHOTT.
